UNITED STATES PATENT OFFICE.

LOUIS H. PERLMAN, OF NEW YORK, N. Y.

DEMOUNTABLE RIM.

1,374,105.

Specification of Letters Patent.

Patented Apr. 5, 1921.

Application filed August 16, 1917. Serial No. 186,525.

To all whom it may concern:

Be it known that I, LOUIS H. PERLMAN, a citizen of the United States, residing at New York, in the county of New York and State of New York, have invented certain new and useful Improvements in Demountable Rims; and I do hereby declare the following to be a full, clear, and exact description of the invention, such as will enable others skilled in the art to which it appertains to make and use the same.

This invention relates to improvements in demountable rims of the type known as cross-cut, and the primary object in view is the adaptation of the rim to receive a manipulating tool.

The particular type of tool adapted for use in manipulating the present improved rim is illustrated and claimed in my co-pending application filed August 16, 1917, Serial No. 186,524, and will, therefore, be described only very briefly so as to render clear the utility of the coöperating parts of the rim.

25 In the accompanying drawing,—

Figure 1 is a side elevation of a fragment of a rim embodying the features of the present invention, the operating tool being shown in position thereon.

30 Fig. 2 is a perspective view of a similar fragment of the rim, the tool being omitted.

Fig. 3 is a fragmentary plan view on an enlarged scale of that portion of the rim provided with the tool-receiving plate.

35 Figs. 4 and 5 are vertical sections taken respectively on the planes indicated by lines 4—4 and 5—5 of Fig. 3.

Fig. 6 is a perspective view of the operating tool detached.

40 Fig. 7 is transverse section taken on the plane indicated by line 7—7 of Fig. 2.

Fig. 8 is a sectional view similar to Fig. 4 of a slightly modified embodiment.

Fig. 9 is a view similar to Fig. 3 showing 45 a slightly modified form of plate.

Referring to the drawing by numerals, 1 indicates a demountable rim having the usual tire-retaining flanges 2 and adapted to sustain a tire having non-extensible beads.

50 To enable the application and removal of such a tire, it is necessary to reduce the effective diameter of the rim temporarily, and to accomplish this result it is customary to cut the rim transversely, as indicated at 3,

55 so that the ends may be caused to overlap each other and the rim be proportionally re-

duced in diameter. The ends of the rim are connected by a latch 4 preferably of the type set forth in my co-pending application Serial No. 121,834, filed September 23, 1916. 60

The latch 4 is fixed to one end of the rim and laps the other end and projects through an aperture therein. Near the end of the rim which carries the latch 4 the valve stem hole is provided and is preferably surrounded by a tubular stud 5 which serves in operation as a driver. A plate 6 is fixed to the inner face of the rim between the stud 5 and the point of attachment of the latch 4. Said plate is offset to form a part 7 spaced from the inner face of the rim 1. A slot 8 is formed in the portion 7 of plate 6 and provided intermediate its ends with laterally curved enlargements 9, 9, so arranged as to form the equivalent of a circular opening 70 having lateral enlargements formed by the ends of the slot 8. This circular enlargement is of just the size to snugly receive a reduced neck or cylindrical portion 10 of a fulcrum post 11 of the operating tool. The 75 post 11 is formed with a button 12 fixed to or integral with the lower end of the neck 10. The button is of less width than length and of a thickness equal to the space between the under face of rim 1 and the part 7 of 80 plate 6, the button being proportioned to pass through the slot 8 so as to be capable of having its end portions swing beneath the part 7 of plate 6, as shown in Fig. 5, and as indicated in dotted lines in Fig. 3. 90

An operating lever 13 is pivoted to the fulcrum post 11 and pivotally engages a cross pin or rod 14 which in turn pivotally carries links 15, 15. The links 15 are loosely hung on the rod 14 and are retained thereon by virtue of the fact that the rod is provided with heads at its ends larger than the apertures in the links 15 through which the rod 14 extends. Spacing sleeves 16, 16, are arranged between the lever 13 and the links 100 15. The free ends of the links 15 are formed with hooks 17, 17, and the links are connected together near said hooks by a bolt 18 engaged by a nut 19 preferably of the winged type. An extension handle 20 is 105 preferably detachably applied to the lever 13 for increasing the leverage for facilitating manipulation of the tool.

The end of rim 1 opposite that to which the latch 4 is connected has its flanges 2 110 formed with apertures 21, 21 adapted to receive the hooks 17.

In operation, the button 12 is inserted through the slot 8 with the lever 13 outstanding in the transverse position indicated in dotted lines in Fig. 3, and the lever is then swung around to a position substantially parallel with the rim, as also indicated in dotted lines in Fig. 3, whereupon the ends of the button 12 will have been swung beneath the overhanging part 7 of plate 6, as indicated by the dotted lines at 12 in Fig. 3. The fulcrum post 11 will thus be effectively anchored to the rim and the hooks 17 are then inserted through the eyes 21 and nut 19 tightened up for drawing the links 15 together sufficiently for preventing accidental escape of the hooks from the eyes. The lever handle 20 is then grasped by the operator and swung through an arc to a position at the opposite side of the fulcrum 11 from that shown in Fig. 1, during which movement the links 15 effect a lifting of their engaged end of the rim for freeing it from latch 4, and then a movement toward the post 11 to an extent sufficient for causing the required collapsing of the rim for reducing the effective diameter thereof so as to enable application and removal of a tire having inextensible beads.

In Fig. 8, I have shown a slightly modified embodiment wherein the parts are identical with those above described with the exception of the form of the under face of the button. The button is seen at 12' and is provided with a parti-globular under face, as indicated at 12''. The rim 1 is formed with a parti-spherical depression 7' for snugly receiving the parti-globular face 12''. The other parts are identical with those described and the same reference numerals have been applied with the understanding that the same description may also be applied.

The anchoring plate for receiving the fulcrum post may be fastened to the rim in

various ways, such as by welding or riveting, and may assume various contours as, for example, instead of being rectangular, as seen in Fig. 3, it may be tapered in opposite directions, as indicated in Fig. 9. In this figure the rim 1' is provided with the plate 6' having tapered ends with only two points of attachment. The structure is otherwise identical with that seen in Fig. 3.

What is claimed is:—

1. The combination of a cross - cut demountable rim and a tool-receiving plate connected with the rim and having a slot with lateral enlargements adapted to accommodate the passage of a post of greater cross section than the width of the main portion of the slot, while leaving outstanding portions of the slot, a portion of the plate being spaced from the rim.

2. The combination of a cross - cut demountable rim and a plate fixed thereto and having a button receiving opening, the rim being formed with a parti-spherical recess in line with the opening for snugly receiving a globular portion of a button.

3. The combination of a cross - cut demountable rim and a tool-receiving plate connected with the inner face of the rim and having an elongated slot, the slot being formed intermediate its ends with curved lateral enlargements for accommodating the passage of the cylindrical portion of a tool of greater diameter than the width of the slot, the plate having portions spaced inward from the inner face of the rim for accommodating a projection from such post between the plate and rim.

In testimony whereof I affix my signature in presence of two witnesses.

LOUIS H. PERLMAN.
